DESIGN FOR A SLIDE BUCKLE

Harold J. Reiter, Chicago, Ill.

Application May 1, 1944, Serial No. 113,421

Term of patent 7 years

(Cl. D17—1)

To all whom it may concern:

Be it known that I, Harold J. Reiter, a citizen of the United States, residing at Chicago, in the county of Cook and State of Illinois, have invented a new, original, and ornamental Design for a Slide Buckle, of which the following is a specification, reference being had to the accompanying drawing, forming a part thereof in which:

Fig. 1 is a plan view of a slide buckle, showing my new design.

Fig. 2 is a side elevational view thereof.

Fig. 3 is a bottom plan view thereof.

Fig. 4 is an end elevational view thereof.

Fig. 5 is an enlarged sectional view thereof, taken substantially on line 5—5 of Fig. 2.

Fig. 6 is an enlarged sectional view thereof, taken substantially on line 6—6 of Fig. 1.

I claim:

The ornamental design for a slide buckle, substantially as shown.

HAROLD J. REITER.
